US0D1071417S

(12) **United States Design Patent** (10) Patent No.: **US D1,071,417 S**
(45) Date of Patent: ** Apr. 15, 2025

(54) **CLEANING MODULE**

(71) Applicants: **QINGDAO HAIER INNOVATION TECHNOLOGY CO., LTD.**, Shandong (CN); **HAIER SMART HOME CO., LTD.**, Shandong (CN)

(72) Inventors: **Hui An**, Shandong (CN); **Zuowei Yi**, Shandong (CN); **Shu Zhou**, Shandong (CN); **Zhaojun Fei**, Shandong (CN); **Linkang Yang**, Shandong (CN); **Zhiqun Feng**, Shandong (CN); **Fei Qin**, Shandong (CN)

(73) Assignees: **QINGDAO HAIER INNOVATION TECHNOLOGY CO., LTD.**, Qingdao (CN); **HAIER SMART HOME CO., LTD.**, Qingdao (CN)

(**) Term: **15 Years**

(21) Appl. No.: **29/829,256**

(22) Filed: **Mar. 3, 2022**

(51) LOC (15) Cl. **15-05**

(52) U.S. Cl.

USPC **D32/25**

(57) **CLAIM**

The ornamental design for a cleaning module, as shown and described.

DESCRIPTION

FIG. 1 is a front-right-top perspective view of the cleaning module;

FIG. 2 is a rear-left-bottom perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

The broken lines shown in the drawings are for portions of the cleaning module and form no part of the claimed design.

1 Claim, 8 Drawing Sheets
